WATCH CONSTRUCTION

John E. Bowen, Akron, Ohio

Application May 8, 1937, Serial No. 141,478

4 Claims. (Cl. 58—107)

This invention relates to watch or clock movements and has for its object the remedying of certain defects in the standard construction of balance wheel and hairsprings.

5 In watches of the better and more expensive types, it is usual to provide the hairspring with what is known as an overcoil, that is to say, the outermost coil of the hairspring is brought up out of the plane of the main body of the hairspring to provide an overlying coil or turn of the wire. This last or outer turn is attached at the 10 point of anchorage on the balance bridge and is engaged by the regulator arm, the innermost turn being attached to the balance wheel.

15 This type of overcoil hairspring is also known as the "Breguet" spring from the name of the inventor. It greatly improves the action of the watch over the use of a plain coil hairspring, but is more unstable laterally than a plain coiled hairspring. For this reason a watch with an overcoil hairspring is more susceptible to jars or blows which throw the hairspring laterally and cause the overcoil to become engaged with the 20 main body of the spring. More frequently, the spring will become entangled with the pins on the regulator arm.

25 It is the purpose of the invention to provide means whereby the tendency of the hairspring to get out of its proper position will be prevented without in any way affecting the operation of the hairspring. Briefly described, the invention consists in the provision of a "Breguet" hairspring overcoil guard which overlies the main body of the hairspring and prevents it from being thrown 30 against the overcoil or the regulator pins. In the preferred embodiment of the invention, this guard is a pin mounted at one end in the balance bridge and extending down to a position just above the main body of the hairspring and then outwardly 35 over the face of the main body to a point just short of the inner circumference of the balance wheel.

40 It is possible to embody the invention in other forms and by specifically different arrangements, 45 that which is shown and described herein being the best known and preferred form of the invention and being set forth so as to enable those skilled in the art to understand and employ the same.

50 In the drawing in which the invention is illustrated as it has been perfected:

Fig. 1 is a plan view of a balance wheel, bridge and hairspring with the invention incorporated therewith;

55 Fig. 2 is a section on the line 2—2 of Fig. 1;

Fig. 3 is an enlarged, partial section on the line 3—3 of Fig. 1; and

Fig. 4 is a detail of the anchorage for the overcoil on the line 4—4 of Fig. 1.

The parts illustrated show a usual or standard 5 form of balance wheel and hairspring, it being understood that the invention may be incorporated in any type of watch movement.

In the drawing, 1 is the lower plate of the movement and 2 the balance bridge between which 10 is located, in the jeweled bearings, the balance wheel 3. In the balance wheel is located the usual coiled hairspring 5 which, in the form shown, is provided with the overcoil 6 indicated by the heavier line in Fig. 1. This overcoil lies above 15 the plane of the main body of the hairspring, as in the standard "Breguet" spring, and is attached to the balance bridge by the post 8, as shown in detail in Fig. 4.

The regulator is of the usual pivoted arm type 20 and is indicated at 10, having the two downwardly extending pins 11—11 which engage the overcoil. It is these pins which frequently are engaged by the hairspring if the watch is jarred.

25 The means which are provided to maintain the body of the spring in its proper position and out of contact with the overcoil and the regulator pins is a guard in the form of the long bent pin 12, which is preferably tapered and bent at an angle 30 at its upper end. The outer end of the guard pin is parallel to the body of the hairspring and lies between the overcoil and the main body. It is preferably extended outwardly so that it approaches closely to the inner rim of the balance wheel 3, but cannot contact the wheel. There is, 35 therefore, no danger of the wheel striking the guard.

40 In the preferred embodiment, the upper or fixed end of the pin 12 is formed obliquely to the main plane of the pin so that it is set at an angle in the socket 14 in the balance bridge. This facilitates the insertion of the pin in the balance bridge. The socket 14 is preferably slightly less in size 45 than the upper or heavier end of the guard pin so that the pin may be permanently fastened in position with a drive fit. This construction is not essential, but is the simplest and most convenient method of mounting the pin in the bridge.

50 It is obvious that some other location may be selected for the guard pin and other means of securing the pin in place be devised. The essential element of the invention is the provision of the separating or guarding means between the main body of the "Breguet" overcoil hairspring 55

and the overcoil so as to prevent lateral displacement of the spring.

What is claimed is:

1. In a watch movement, the combination of a balance wheel and a hairspring provided with a spaced overcoil, and a pin fixed on the bridge and extending from a point radially inward of the rim of the balance wheel, through the overcoil and projecting over the main body of the hairspring.
2. In a watch movement, the combination of a balance wheel and a hairspring provided with a spaced overcoil, and a pin fixed on the bridge and extending from a point radially inward of the rim of the balance wheel, through the overcoil and projecting over the main body of the hairspring to a point adjacent the rim of the balance wheel.

3. In a watch movement, the combination of a balance wheel and bridge, of a hairspring provided with a spaced overcoil, and a pin having an oblique terminus fixed in the bridge and an extension parallel to and lying over the main body of the hairspring and between the hairspring and the overcoil.

4. In a watch movement, the combination of a balance wheel and bridge, of a hairspring provided with a spaced overcoil, and a pin having an oblique terminus fixed in the bridge and an extension parallel to and lying over the main body of the hairspring and between the hairspring and the overcoil, the end of the pin projecting to a point adjacent the inner rim of the balance wheel.

JOHN E. BOWEN.
